UNITED STATES PATENT OFFICE.

WALTER AUGUST SCHMIDT, OF LOS ANGELES, CALIFORNIA, AND LINN BRADLEY, OF EAST ORANGE, NEW JERSEY, ASSIGNORS TO RESEARCH CORPORATION, OF NEW YORK, N. Y., A CORPORATION OF NEW YORK.

APPARATUS AND METHOD FOR RECTIFYING HIGH-TENSION ALTERNATING CURRENT.

1,340,502.

Specification of Letters Patent.

Patented May 18, 1920.

Application filed September 15, 1915. Serial No. 50,793.

To all whom it may concern:

Be it known that we, WALTER AUGUST SCHMIDT and LINN BRADLEY, citizens of the United States, residing, respectively, at Los Angeles, in the county of Los Angeles, State of California, and East Orange, in the county of Essex, State of New Jersey, have invented a new and useful Apparatus and Method for Rectifying High-Tension Alternating Current, of which the following is a specification.

This invention relates to the rectification of alternating currents, particularly for application in connection with the precipitation of suspended matter from gases. Such precipitating operations, when carried out on a commercial scale, require the use of such high potentials and such large surface of electrodes, that the electrostatic capacity of the operating circuit becomes an important factor in the operation of the system. When a high tension electromotive force is suddenly applied to a circuit of high capacity and appreciable conductance, the charging of the capacity requires an appreciable time and there is a tendency of the charges to surge back into the line immediately after such charging is completed. An important object of our invention is to provide for minimizing such back surging of the charge, and to insure that substantially the whole energy of the charge will be retained in the apparatus except in so far as it is utilized in discharge through the apparatus. For this purpose we provide for breaking the connection to the apparatus, preferably at the rectifier, as soon as the charging of the apparatus is completed, and the charging current is therefore substantially reduced to zero. This not only safeguards the line transformer and rectifier from high potential surges, but breaks the rectifying connection at the most favorable time for elimination or mitigation of sparking or arcing at the rectifier contacts, namely the time of minimum current flow.

A further object of the invention is to provide for controlling the duration of the periods in which current is being taken from the line, either for the purpose above set forth or for any other purpose.

Another object of the invention is to provide rectifying means of simple construc-

tion and presenting minimum loss by windage or otherwise.

Another object of the invention is to provide improved means for shifting the phase of the rectifier relatively to the phase of the alternating current supplied thereto.

In the accompanying drawings:

Figure 1 is a side elevation of a rectifier embodying our invention.

Fig. 2 is a section on line x^2-x^2 in Fig. 1.

Fig. 3 is a section on line x^3-x^3 in Fig. 2.

Fig. 4 is an elevation of one of the variable-length contact shoes.

Fig. 5 is a longitudinal section of the brush holder for making connection with the shaft.

Fig. 6 is a partial vertical section of the rotative member and shaft of the rectifier.

Fig. 7 is a side elevation of a portion of the rotative member.

Fig. 8 is a front elevation of another form of the invention.

Fig. 9 is a side elevation of the device shown in Fig. 8.

Fig. 10 is a front elevation of another form of the invention.

Fig. 11 is a side elevation of the form of the invention as shown in Fig. 10.

Fig. 12 is a rear elevation of the stationary member shown in Fig. 11.

The rectifier comprises a stationary member 1, mounted on a frame 2, and a rotative member 3 carried by a shaft 4, which is journaled in bearings 5 on said frame. Frame 2 may consist of a base and standards 2' on said base, said standards being provided with the bearings 5 for shaft 4 and 90 with bearings 7 on which the stationary member is mounted so as to be angularly adjustable around the axis of the rotative member.

Stationary member 1 preferably consists of end spiders or members 8 rotatively mounted on the respective bearings 7 and longitudinal rods 9 and 9' connecting said spiders 8. Said rods are preferably arranged in pairs, rigidly connected to arms 100 8' of spider 8. One of these pairs of rods (9') may be of metal, the other rods 9 being of insulating material. Contact holders are mounted on the respective pairs of rods, each holder comprising a clamp 10 rigidly secured to a pair of rods 9 or 9', bolt 11,

said bolt also clamping to said holder a bar 12, which is slotted as at 12' to receive the bolt and which carries a contact shoe 14. To provide for adjustment of the 5 length of the contact shoe in the direction of motion of the rotor, said shoe may be provided with an extension 14', formed as a segment slotted to slide on bolts 15 on member 14, and means are preferably provided 10 for adjustment of these parts while the machine is in motion, such means consisting for example, of a pinion 16 engaging a rack 13 on each member 14', said pinion being operated, through an insulating shaft, 40, 15 by manual operating means 41. The stationary frame 1 is also preferably provided with means for angular adjustment thereof while the machine is in motion, said means comprising, for example, a rod 42 pivoted thereto, and adjustably clamped in a guide 20 43, by clamp screw 44.

Shaft 4 is preferably grounded, for example, by a brush 50, mounted in a holder 51 on bearing 5, and pressed against the 25 shaft by a spring 52. In order to provide the requisite insulation for the rotor, shaft 4 may be covered with an insulating sleeve 4' of any suitable insulating material. Rotative member 3 preferably consists of a 30 disk of insulating material, such as hard fiber, treated by impregnation with suitable insulating material, so as to give it the necessary high insulating property. The apparatus shown is adapted to rectify a 35 single phase alternating current, using four stationary contact shoes 14 on the stationary member, and two conductors on the rotative member, said conductors being formed, for example, as metallic segments 18 secured to 40 the disk 3, and provided with radial projections 17 forming a pair of contact members for each conductor. Disk 3 may be mounted on shaft 4 by means of a hub 20 on said disk, having split tubular end portions 20' 45 formed with taper screws engaged by nuts 22 to clamp the hub to the shaft.

The rotative member is rotated in synchronism with the alternating current which is to be rectified. This is effected by connection of 50 shaft 4 to a motive device operating in synchronism with such current. For this purpose we may connect the shaft 4 to the shaft 25 of a motor generator set, indicated at 26 in Fig. 2, the generator member 28 of which is 55 connected to the primary circuit 30 of a step-up transformer 31. The secondary winding of said transformer is connected at opposite sides thereof, by wires 32 and 33 respectively, to two of the contact shoes 14 60 on opposite sides of the stationary member. One of the other two opposite contact shoes may be grounded as at 34, and the other is connected by wire 37 to the high tension electrodes 38 of a precipitating apparatus, 65 the opposite electrodes 38' thereof being

grounded as indicated at 39. A synchronous motor may be used instead of a motor generator set.

Such precipitating apparatus may be of any usual or suitable type, and is only indicated diagrammatically in the drawing. In the case of large commercial installations, such precipitating apparatus presents large electrostatic capacity as well as considerable conductance, the apparatus acting 75 in fact as a leaky condenser.

The parts of the stationary members through which the current passes to the conductors of the rotative member are here called contact members or shoes, but it will 80 be understood that with the high tensions used in connection with this apparatus, it is not necessary for the rotative conductors to actually contact with these stationary members, and in general they will be so arranged 85 as to pass the stationary shoes without touching, but sufficiently close to enable the current to pass through the intervening medium. While it may in some cases be desirable to form the conductors on the 90 rotative member with contact members 17 projecting therefrom so as to break connection with the stationary members at two points simultaneously, for each rotative conductor, we may, in other cases use 95 a continuous segment making connection throughout the whole or any part of its length, with the stationary members. Furthermore, our invention is not limited to two pairs of rotative conductors, or of 100 stationary conductors, but may comprise any desired number of such conductors, connected to accomplish the same result as the construction above described, it being understood that in any case the rectifier will be 105 driven at such speed that its period of rectification synchronizes with the period of alternation of the supply current.

The operation of the apparatus above described is as follows: The rotative member 110 is rotated by the shaft 4 in such manner that at a certain point in each half wave of the alternating current, the conductors of the rotative member occupy the positions shown in Fig. 2, so that each of said conductors 115 bridges or makes a connection across the space between one of the stator shoes connected to the supply circuit, and the stationary shoe at the rear thereof, thereby putting the supply circuit momentarily in 120 connection with the load and causing current to flow in a certain direction through the load, and during a corresponding point in the next succeeding half wave, the conductors of the rotative member occupy positions 125 90 degrees in advance of the positions just described, so as to bridge or connect across from each stationary shoe connected to the supply circuit, to the load-connected stationary shoe in advance thereof; the con- 130

nections of the supply-connected stationary shoes to the load connected stationary shoes being thereby reversed, and as the polarity of the stationary shoes has been reversed at the same time, the electric current impulse delivered to the load is in the same direction as before.

In carrying out our method of supplying current through a load acting as a leaky condenser, we vary the angular position of the stationary member, so as to change the time of make and break relatively to the phase of the supply current, and vary the length of the contact shoes, (by the adjusting means 16 above described) so that at each half wave of the alternating current the effective connection between the supply circuit and the load, through the rectifier, is maintained for a sufficient time to charge the load, acting as a capacity, to substantially the momentary potential difference of the supply circuit, the charging current being then a minimum (being only that due to the leakage from the load, acting as a corona load or resistance) and at this moment the connection is interrupted by the rectifier so that surging is reduced to a minimum by reason of the smallness of the current at the moment of break and also by reason of the fact that the load, acting as an electrostatic capacity, and being momentarily at the same potential difference as the transformer, does not tend to either draw current from the transformer, or to discharge back to the transformer. This time of interruption is also the most favorable for successful operation of the rectifier as it minimizes the sparking or arcing at the moment of break, and the operator may determine the proper adjustment of the stationary members, as to length and angular position, by noting the sparking or arcing action, and adjusting for minimum thereof.

The above described construction of the rotative member of the rectifier, in which an insulating disk is used as the means for carrying the rotative member contacts, is of great advantage in that it provides high insulation together with ample mechanical strength, and also in that it reduces windage loss to a minimum.

Another embodiment of our invention is illustrated in Figs. 8 and 9, wherein the stationary member is shown as comprising four arms 41 carried by a hub 43, whose shaft 44 is mounted to turn in a bearing 45, and four supplementary arms 41' carried by a hub 43' whose shaft 44' extends through the shaft 44, the respective arms 41 and 41' carrying the contact shoes or members 46 and 46'. Arms 41 and 41' are preferably formed as rods of insulating material and the shoes 46 and 46' may be formed as plates carried by rods 47 and 47' mounted on arms 41 and

41' by clamping means 48 and 48'. Springs or flexible connections 50 connect each of the arms 41 with one of the arms 41' so that the contacts 46 and 46' carried by the two arms connected by such spring form in effect a single contact member, whose effective length may be varied by rotating the set of arms relatively to the set 41 so as to vary the distance of each contact 41' from the corresponding contact 41. Means such as arms 52 and 52' may be provided on the respective shafts 44 and 44' to adjust the angular position of the respective sets of arms 41 and 41'. Said arms may be operated by rods 53, 53' from any suitable controlling means.

The rotative member in this form of our invention may consist of an insulating disk 55 provided with contact segments 58 and carried by a hub 56 on the shaft 57 of a motor, such as a synchronous motor 59 or other motive means adapted to rotate in synchronism with the alternating current which is to be rectified. The segments 58 in this case are shown as of uniform height throughout their length. And this construction of the segments is of a special advantage for the reason that the outer edge of each segment remains close to the shoes or conductors 41 and 46 throughout the time of closure of contact, and at uniform distance therefrom, thereby maintaining a constant zone of conducting gas at the gap between the stationary shoes, or conductors, and said segments, and reducing to a minimum the oscillation or surging of current due to sudden changes of resistance at the break or gap. The circuit connections to the respective contact members 46 are the same as above described, and the operation is the same, except that by the adjusting or shifting means 52' all of the contact members 46' may be shifted simultaneously with relation to the contact members 46, so as to vary the duration of contact.

Instead of making all of the stationary member contacts on two relatively adjustable members, as in Fig. 8, we may make only one of the opposite pairs of contacts on relatively adjustable members, as shown in Fig. 10, the contacts 61 of the stationary member being carried by opposite arms 62 connected together and rotatably mounted on bearing 65, and the other contact member of the stationary member comprising two sets of contact shoes 66 and 66' carried respectively by opposite arms 67 and opposite arms 67' which are independently rotatable on the bearing 65, each shoe 66 being connected by a spring or flexible member 68 to the adjacent shoe 66'. The rotative member 70 may be similar to that above described.

Any suitable means may be provided for adjusting the arms of the device shown in

Fig. 10, for example, the means shown in Figs. 11 and 12, in which two of the arms 67, 67' are shown as extending downwardly from the shaft mounting therefor, and provided with swivel nuts 75 engaged by reversely threaded portions 76, 76' on a shaft 77 rotatably mounted in an arm 78 extending from the cross arm 62. The shaft 77 is provided with an operating handle 79, whereby the shaft may be moved bodily to turn all of the arms of the stationary member, in unison about the axis of the rotor 70, so as to change the time of make or break, or, by rotating the shaft 77, to move the arms 67 67' of each pair, closer together or farther apart so as to vary the duration of contact. The parts may then be set into position by tightening nut 80 on shaft 65, which constitutes the bearing for said parts.

20 What we claim is:

1. A rectifier for high tension alternating current comprising supporting means provided with bearings, a shaft mounted to rotate in said bearings, an insulating rotary disk carried by said shaft and provided with peripheral conducting segments, a stationary member mounted for angular adjustment around the axis of said shaft and provided with means for holding it in angularly adjusted position and with insulating rods, and conductors mounted on the respective insulating rods and provided with shoes extending adjacent to the path of the con-

ducting segments on the rotary disk, said shoes having, respectively, supply circuit 35 connections and load connections.

2. A rectifier according to claim 1 wherein the said shoes are movably mounted on the supporting conductors therefor, for adjustment toward or from the periphery of 40 the disk and are provided with means for clamping the same in adjusted position.

3. A rectifier for high tension alternating currents, comprising supporting means provided with two bearings, a shaft mounted 45 to rotate in said bearings, an insulating rotary disk carried by said shaft and having peripheral conducting segments, two spiders rotatably mounted on the respective bearings, insulating rods and a conducting rod 50 connecting said spiders to form a frame angularly adjustable around the axis of rotation of said disk, and shoes mounted, respectively, on said insulating rods and on the conducting rod and extending adjacent to 55 the path of rotation of said conducting segments so as to be connected in pairs by said segments, said shoes having, respectively, supply circuit and load circuit connections.

4. A rectifier according to claim 3 wherein said rods are provided in pairs, and a shoe supporting means is clamped on each pair of rods to rigidly hold the shoes.

WALTER AUGUST SCHMIDT.
LINN BRADLEY.
